SPRING HINGE AND ADJUSTABLE LEAF

Emil Bommer, Brooklyn, N. Y.

Application April 28, 1932. Serial No. 607,928

5 Claims. (Cl. 16—181)

This invention relates to single and double acting spring hinges, and more particularly to improvements in spring hinges of the so-called clamp-flanged type which are used more especially for hanging doors to marble, slate or stone partitions or stiles and for similar purposes.

The invention has for its object and purpose to provide a simple, practical and efficient leaf of the so-called clamp-flanged type for accommodating the partition or stile, and to provide in this regard a construction having novel features of adjustability by means of which the stile may be snugly and firmly embraced without the necessity of cutting, chipping, mortising or otherwise preparing the stile for the application of the hinge thereto.

In carrying my improvements into effect, the flange adjacent the hinge barrel is mounted for relative adjustment with respect to the other 20 of the flanges and with respect to the leaf web, the adjustable connection for this purpose being provided directly between the leaf web and the adjustable flange and consisting in the example herein given of projections on the leaf web which 25 engage between longitudinal guide walls extending transversely of the adjustable flange. For the production of the longitudinal guide walls, the adjustable flange is expanded adjacent the leaf web, the expansion being on the outside and 30 toward the hinge barrel to provide an outside apron behind which the adjustable connection is concealed irrespective of the adjustment of the adjustable flange.

Another object and purpose of my invention is 35 to provide an adjustable flange which is adjustable in two directions; first, along the web toward and away from the stationary flange, and secondly, in a plane at right angles or substantially at right angles to the web in order to compensate for any malformation in the angularity 40 of the sides of the stile with respect to the inner edge thereof and at the same time to provide for accurate alignment of the bolt-receiving holes in the adjustable flange with the bolt-receiving 45 holes of the stationary flange.

With the foregoing and other objects in view, the invention consists of the novel construction, combination and arrangement of parts as hereinafter more specifically described with reference 50 to the example illustrated in the accompanying drawing, wherein like reference character denote corresponding parts throughout the several views, and in which:—

Figure 1 represents a perspective view of a 55 spring hinge made in accordance with the pres-

ent invention, parts being broken away and the hinge leaves being shown in open or spread relation;

Fig. 2 is a cross sectional view on the line 2—2 of Fig. 1, but with the hinge leaves in the relationship they occupy when the door is closed, fragments of the door and stile being shown in dot-dash outline;

Fig. 3 is an elevational view, showing the stile leaf with the adjustable flange removed;

Fig. 4 is a detail elevational view of the adjustable leaf, showing the longitudinal guide walls on the expanded portion thereof; and

Fig. 5 is a vertical cross section, taken on the line 5—5 of Fig. 1.

Referring now to the accompanying drawing, the spring hinge in which I have illustrated a simple and practical example of my improvements as reduced to practice, comprises a door leaf 10, a stile leaf or web 11 and a hinge barrel 12, the door leaf 10 and hinge barrel 12 being made integral and the leaf or web 11 having integral lugs or ears 13 which are located at opposite ends of the hinge barrel. Arranged within the hinge barrel is a hinge pin 14 and a coiled 75 tensioning spring 15; and disposed between the upper end of the hinge barrel 12 and the top ear or lug 13 is a tensioning collar 16 by means of which to tension the spring in a manner well-known in the art. All of these parts may be of 80 85 well-known or approved construction.

The stile leaf or web 11 is made with a laterally projecting flange 17 in a plane substantially at right angles to the plane of the web 11. This flange extends along the outer edge of the web 90 and will be hereinafter referred to as the stationary or fixed flange.

Opposing the flange 17 on the same side of the web 11 is a flange 18 which will be hereinafter referred to as the adjustable flange. The web 11 together with the stationary flange 17 and adjustable flange 18 forms the so-called clamp-flanged type of leaf in which is received the edge portion 19 of the stile or other element which is to be secured to and between the two flanges.

The construction of means by which I provide, in accordance with the present invention, for the adjustment of the flange 18 consists in forming the web 11 adjacent the hinge barrel with projections or studs 20 and 21. For receiving the 105 projections or studs 20 and 21, the inner edge 22 of the flange 18 is provided with longitudinal recesses 23 and 24, respectively; the recess 23 being defined by longitudinally extending guide walls 23', 23', while the recess 24 is formed by 110

similarly extending guide walls 24', 24''. As clearly shown in Fig. 4, these recesses and guide walls extend transversely of the flange 18, so that when the recesses have been applied to the studs 5 the flange 18 can be adjusted along the web 11 toward or away from the opposite flange 17 in order to accommodate the thickness of the stile portion 19.

It will be noted that the studs 20 and 21 do 10 not project at right angles from the web 11, but are inclined from the perpendicular; the two studs in the present embodiment inclining or sloping toward each other so that the distance between their outer ends will be less than the 15 distance between their base portions. For slidably accommodating the studs, the recesses in the flange 18 and hence the guide walls defining the recesses are appropriately inclined from the perpendicular; the two pairs of walls 23', 23'' and 20 24', 24'' inclining in opposite directions.

For the production of the transversely extending guide walls, the flange 18 is formed at its inner end 22 with an apron extension 25 which projects toward the hinge barrel. This apron 25 extension is not even with the inner edge 22 of the flange, but is set back from the plane thereof and constitutes the base for the transversely extending guide walls. According to this form of construction, the free edges of the guide walls 30 are even with the inner edge 22 of the flange and the apron extension is so spaced from the plane of the inner edge 22 that the recesses will be of a greater depth than the length of the studs, as clearly shown in Fig. 5. By reason of this arrangement, the flange 18 is not only adjustable toward and away from the stationary flange 17, but also has a degree of adjustment toward and away from the web, so that the bolt-receiving eyes 26 of the flange 18 can be brought into precise alignment with the bolt-receiving eyes 27 35 of the stationary flange, while at the same time compensating for any malformation in the angularity of the faces 28, 28'' of the stile with respect to the outer edge 28'' thereof which abuts 40 against the web 11. Notwithstanding the inclination of the studs, the adjustable hinge is readily applied thereto by disposing the inner edge 22 of the flange in close proximity to the barrel and then applying the recesses to the studs by giving 45 the flange a turning action until the flange assumes a position substantially at right angles to the web. The apron extension 25 not only serves 50 as a base for the transversely extending guide walls but also serves as means for concealing the adjustable connections between the web and flange irrespective of the position of adjustment 55 of the flange.

The adjustable flange of my invention is simple in construction and economical in manufacture, 60 and while possessing the advantage of being adjustable in one direction to accommodate the thickness of the stile and in another direction to compensate for any malformation in the sides 65 of the stile, it has the further advantage, because of the apron extension, of concealing the adjustable connections irrespective of the relative adjustment of the flange.

While my invention has been illustrated and described in particular in connection with the 70 stile leaf, it will be obvious that it may be produced in connection with the door leaf, or also that it may be produced in connection with an adjustable leaf for a door strike or similar device.

Although I have herein disclosed and described 75 only one example and practical embodiment of

my improvements as reduced to practice, it will be recognized that the disclosure given is an example only, and is susceptible to more or less modifications in the form, proportions and relative arrangement of the various parts, and I, therefore, reserve the privilege of resorting to all such legitimate changes therein as may be fairly incorporated within the spirit and scope of the invention as claimed.

I claim:—

1. In a hinge of the character described, the combination of a leaf web having a laterally projecting flange, a second flange disposed laterally of the web in opposition to the first flange and having an extension adjacent the web extending laterally from the flange and substantially parallel with the web, a pair of lateral projections on the face of the web, longitudinal guide walls on said extension defining a pair of open longitudinal recesses open to the face of the web and in which the projections are received, said guide walls and recesses extending transversely of the plane of the flange thereof and being in such direction of greater extent than the projection to permit adjustment of the flange upon the projections in a direction toward and away from the first flange, and the members of said pairs of projections with their cooperating recesses being inclined from the perpendicular with respect to the face of the web and in opposite directions with respect to each other to prevent separation of the second flange when moved in a direction laterally of the web. 80 85 90 95 100 105

2. In a hinge of the character described, the combination of a barrel, a leaf web extending therefrom and having a laterally projecting flange along its outer edge, a second flange adjacent the barrel disposed laterally of the web in opposition to the first flange, an apron extension on the second flange extending laterally therefrom towards the barrel and substantially parallel with the web, a lateral projection on the web, longitudinal guide walls on said extension defining an open recess in which the projection is received, said guide walls extending transversely of the plane of the second flange to provide for the adjustment of the second flange toward and away from the first flange and also laterally of the web, said apron being shaped to conceal the projection and its guide walls behind the barrel irrespective of the position of adjustment of the second flange. 110 115 120 125 130

3. In a hinge of the type including a barrel and a leaf web having a laterally projecting flange along its outer edge, the combination of a second flange disposed edgewise to the face of the web adjacent the barrel and in parallel relation to the first flange, transverse guide walls on the inner edge portion of the second flange extending toward the barrel and adapted to contact the face of the web, said guide walls being shaped to form open recesses open to the face of the web, and projecting members on the face of the web extending within said recesses, said projections being of less length than the guide walls to permit movement of the second flange by moving the guide walls along said projections. 135 140

4. In a hinge of the type including a barrel and a leaf web having a laterally projecting flange along its outer edge, the combination of a second flange disposed edgewise to the web adjacent the barrel and in parallel relation to the first flange, an apron extension on the inner edge portion of the second flange projecting toward the barrel and provided with transversely extending guide walls forming open recesses facing the web, and 145 150

members projecting from the face of the web and engaging within said recesses for guiding adjustment of the second flange toward and away from the barrel in parallel relation to the first-mentioned flange.

5. In a hinge of the type including a barrel and a leaf web having a laterally projecting flange along its outer edge, the combination with a second flange disposed edgewise to the web adjacent to the barrel and in parallel relation to the first flange, of an apron extension on the inner edge portion of the second flange projecting toward the

barrel and provided with transversely extending recesses facing the web, projections on the face of the web engaging within said recesses, said projections being of less length than the recesses and providing means whereon to guide the second flange for adjustment toward and away from the barrel and in parallel relation to the first flange, and wall portions on said apron closing the ends of said recesses adjacent the barrel for concealing the projections within the recesses at the barrel side of said second flange.
